United States Patent Office

Des. 184,651
Patented Mar. 17, 1959

184,651

BOWL

Cecil B. Woofter, Minneapolis, and Don Harley, St. Paul, Minn., and Arthur Salm, Chicago, Ill., assignors to Arthur Salm Inc., Chicago, Ill., a corporation of Illinois

Application August 8, 1958, Serial No. 52,120

Term of patent 14 years

(Cl. D44—15)

Fig. 1 is a perspective view of a bowl showing our new design;

Fig. 2 is a plan view of the bowl of Fig. 1;

Fig. 3 is a side view of the bowl of Fig. 1; and

Fig. 4 is an end view of the bowl of Fig. 1.

We claim:

The ornamental design for a bowl, substantially as shown.
